UNITED STATES PATENT OFFICE.

CHARLES T. WESTLAKE, OF ST. LOUIS, MISSOURI, ASSIGNOR TO LOCOMOTIVE TENDER FRAME COMPANY, OF ST. LOUIS, MISSOURI, A CORPORATION OF DELAWARE.

LOCOMOTIVE-TENDER UNDERFRAME.

1,378,204.

Specification of Letters Patent. Patented May 17, 1921.

Application filed November 19, 1919. Serial No. 339,149.

To all whom it may concern:

Be it known that I, CHARLES T. WESTLAKE, a citizen of the United States, residing at St. Louis, Missouri, have invented a certain new and useful Improvement in Locomotive-Tender Underframes, of which the following is a full, clear, and exact description, such as will enable others skilled in the art to which it appertains to make and use the same, reference being had to the accompanying drawings, forming part of this specification.

My invention relates generally to locomotive tenders, and more particularly to the bed or underframe that supports the tank and superstructure of the tender, the principal objects of my invention being to provide a relatively strong, rigid and substantial underframe; to construct the underframe in a single piece, preferably by casting, thereby simplifying manufacture and minimizing the cost of production and providing a construction which eliminates all joints and connections between assembled parts; to form integral with the underframe various brackets and bearings adapted to receive essential parts that are associated with and carried by the underframe; to provide a tender underframe that is particularly designed for use in connection with six wheel trucks and which arrangement requires a certain amount of clearance between the body bolsters of the underframe and the wheels on the middle axles of the trucks; to arrange and form the various parts of the underframe so as to obtain greatest strength at the points where the greatest service stresses and strains are produced; and, further, to construct the rear end of the tender frame so as to resist to the maximum degree the stresses produced by eccentric loads due to the elevated position of the buffing casting.

With the foregoing and other objects in view, my invention consists in certain novel features of construction and arrangement of parts, hereinafter more fully described and claimed, and illustrated in the accompanying drawings, in which—

Figure 1 is a plan view of a tender underframe of my improved construction.

Fig. 2 is a longitudinal section taken approximately on the line 2—2 of Fig. 1.

Fig. 3 is a side elevational view of the underframe.

Fig. 4 is an enlarged vertical section taken approximately on the line 4—4 of Fig. 1.

Fig. 5 is an enlarged detail section taken approximately on the line 5—5 of Fig. 1.

Fig. 6 is an enlarged section taken approximately on the line 6—6 of Fig. 1.

Fig. 7 is an elevational view taken looking in the direction indicated by the arrow 7 in Fig. 1.

Fig. 8 is a cross section on the line 8—8 of Fig. 7.

Fig. 9 is a cross section taken on the line 9—9 of Fig. 6.

The underframe contemplated by my invention is formed in a single piece, preferably by casting, and as illustrated said underframe comprises the following principal members, to-wit—a pair of side sills 10, a front end sill 11, a rear end sill 12, a pair of substantially parallel longitudinally disposed center girders 13, a pair of divided or double body bolsters 14, and a transversely disposed rail 15 located preferably at a point midway between the double body bolsters.

The side sills 10 may be of any desired cross sectional shape, although I prefer to make them of I-beam shape and with webs vertically disposed. Likewise the main body portions of the center girders 13 or 70 those portions between the double body bolsters 14 are of I-beam shape in cross section and they are of the fish-belly type, that is, their central portions are substantially 75 deeper than their end portions, thereby providing an exceptionally strong construction 80 where the greatest strength is required.

Thus the end portions of the center girders or those portions lying between the inner members of the double body bolsters 95 14 and the end sills 11 and 12 are relatively shallow and which arrangement is necessary by reason of the fact that there is less available space immediately over the six wheel trucks which support the underframe and 100 parts carried thereby.

Each divided or double body bolster 14 comprises a pair of transversely disposed members which are substantially of I-beam shape in cross section, and said members being spaced a sufficient distance apart to provide the necessary clearance for the wheels 105 of the middle axles of the trucks. (See Fig. 6.)

Longitudinally disposed portions 17 of 110

the arched members 16 provide bearings for the side bearings of the truck frames. (See Fig. 9.)

The rear end sill 12 is a hollow member and preferably of box shape in cross section and its upper portion extends a substantial distance above the top surface of the tops forming the bed or underframe. Obviously, this end sill performs the functions of a buffering beam and in order to take care of the stresses produced by eccentric loads due to the elevated position of this beam, the adjacent end portions of the center girders are provided with deep vertical webs 18 and 15 with horizontally disposed top and bottom flanges 19 which gradually increase in width toward the adjacent member of the double body bolster. (See Figs. 1, 2 and 5.)

The front end sill 11 is preferably hollow and of box-shape in cross section, and formed integral therewith and with the immediately adjacent end portions of the center girders 13 is a rearwardly projecting housing 20, the greater portion of which is disposed below said front end sill and the center girders. The chamber or pocket 21 within this housing is open at its outer end and it is adapted to receive a drawbar (not shown), the latter being pivotally connected to the underframe by means of a pin which is seated in vertically disposed bearings 23 that are formed in the top and bottom walls of the housing 20. These drawbar connecting pin bearings are located a slight distance to the rear of the front end sill 11. (See Figs. 1 and 4.)

Formed integral with and arranged below the front portion of the drawbar pocket housing 20 is a secondary housing 24 that is provided with a horizontally disposed opening or pocket 25 that is adapted to receive the end portion of a safety bar (not shown), and which latter is connected to the housing by a pin that occupies vertically aligned bearings or seats 26, the same being formed in the bottom of housing 20 and in the bottom of secondary housing 24. These pin seats or bearings are located a short distance in front of the bearings or seats 23 and preferably below the rear portion of front end sill 11.

The lower central portions of the members forming the double body bolsters 14 are connected by integrally formed horizontally disposed plates 27 and secured to the central portions thereof in any suitable manner are center bearings 28 that are adapted to receive corresponding bearings on the frames of the trucks which support the tender underframe or bed.

Formed in the upper outwardly projecting flanges of the side sills 10 adjacent to their ends are elongated openings 29 that are adapted to receive tank anchoring lugs, the latter being secured to the webs of the side sills in any suitable manner. (See Fig. 8.)

65 A locomotive tender underframe of my

improved construction combines great strength and rigidity with minimum weight, and said underframe can be easily and cheaply produced owing to the fact that it can be readily cast in a single piece, and the 70 elimination of joints between the parts which form said underframe entirely overcomes structural weaknesses that invariably develop where an assembled or fabricated structure is subjected to service strains and 75 vibration.

The various parts entering into the construction of my improved underframe are arranged and formed so as to resist to a maximum degree the strains and stresses to 80 which the underframe is subjected while in service, and by forming said underframe with divided or double body bolsters, it is particularly adaptable for use in connection 85 with six wheel trucks.

It will be readily understood that minor changes in the size, form and construction of the various parts of my improved locomotive tender underframe can be made and substituted for those herein shown and described, without departing from the spirit of my invention, the scope of which is set forth in the appended claims.

I claim:

1. A locomotive tender underframe cast 95 in a single piece and provided with integrally formed longitudinal sills, end sills, and double body bolsters.
2. A locomotive tender underframe cast in a single piece and provided with integrally 100 formed longitudinal sills, end sills, and double body bolsters, and side bearing members formed integral with and arranged between the members of each double body bolster.
3. A locomotive tender underframe cast in 105 a single piece and provided with integrally formed longitudinal sills, end sills, and double body bolsters, and side bearing members formed integral with said double body bolsters and having their central portions raised 110 to provide clearance for the wheels of the truck.
4. A locomotive tender underframe cast in a single piece and provided with integrally 115 formed longitudinal sills, end sills, and double body bolsters, and arched side bearing members supported by said double body bolsters.
5. A locomotive tender underframe cast in a single piece, said underframe including 120 double body bolsters, end sills, and a plurality of center girders having relatively deep central portions.
6. A locomotive tender underframe cast in a single piece, said underframe including 125 double body bolsters and a plurality of center girders, the central portions of which are substantially deeper than the end portions.
7. A locomotive tender underframe cast 130

in a single piece and comprising side sills, end sills, center girders, and double body bolsters.

8. A locomotive tender underframe cast in a single piece and comprising side sills, end sills, center girders, double body bolsters, and side bearing members.

9. A locomotive tender underframe cast in a single piece and including a housing in which is formed a drawbar pocket and a safety bar pocket, said safety bar pocket and said draw-bar pocket being formed on different horizontal planes in said housing.

10. A locomotive tender underframe cast in a single piece and including a housing in which is formed a drawbar pocket and a safety bar pocket, said safety bar pocket being arranged below the forward portion of said drawbar pocket.

11. A locomotive tender underframe cast in a single piece and provided with superimposed drawbar and safety bar receiving pockets, said pockets being provided with seats adapted to receive the drawbar and safety bar connecting pins, the seats for the drawbar pin being disposed to the rear of the seats for the safety bar pin.

12. A locomotive tender underframe cast in a single piece and provided with inter-

grally formed parts in which are formed 30 seats adapted to receive the pins which serve as points of attachment for a drawbar and a safety bar, the seats for the safety bar pin being disposed below and in front of the seats for the drawbar attaching pin.

13. A locomotive tender underframe cast in a single piece and provided with a rear end sill, a portion of which is elevated with respect to the top surface of the under-frame, a pair of longitudinal center girders 40 forming a part of the underframe, the end portions of which center girders adjacent to the rear end sill are reinforced by tapered horizontal flanges to resist stresses produced by eccentric loads due to the elevated position of said end sill.

14. A locomotive tender underframe cast in a single piece and comprising side sills, center girders, end sills, double body bolsters, side bearing members carried by said 50 double body bolsters, and a housing adjacent to the front end sill, which housing is provided with pockets adapted to receive a drawbar and a safety bar.

In testimony whereof I hereunto affix my 55 signature this 14th day of November, 1919.

CHARLES T. WESTLAKE.
